UNITED STATES PATENT OFFICE.

HJALMAR ZAHL, OF DULUTH, MINNESOTA, ASSIGNOR OF ONE-HALF TO CHARLES S. OLSON, OF DULUTH, MINNESOTA.

HOPPER-BOTTOM DUMP-CAR.

1,097,577.

Specification of Letters Patent. Patented May 19, 1914.

Application filed December 6, 1913. Serial No. 305,058.

To all whom it may concern:

Be it known that I, HJALMAR ZAHL, a citizen of the United States, residing at Duluth, in the county of St. Louis and State of Minnesota, have invented certain new and useful Improvements in Hopper-Bottom Dump-Cars, of which the following is a specification, reference being had therein to the accompanying drawing.

10 My invention relates to improvements in hopper-bottom dump cars.

The object of my invention is to provide means whereby my improved dumping device may be readily applied to a form of 15 hopper cars now in common use.

Another object of my invention is to provide a hopper-bottom dump car whereby the discharging members of the car is more readily operated and, at the same time, materially increasing the carrying capacity of 20 the car, and rendering the action of discharging absolutely positive.

A still further object of my invention is to provide a simple, cheap and effective car 25 of this character having certain details of structure and combination of parts herein-after more fully pointed out.

In the accompanying drawings forming part of this specification: Figure 1 is a side 30 elevation of a car equipped with my improved hopper and discharging means. Fig. 2 is a central cross sectional view of the same showing one side door open and one closed. Fig. 3 is a cross section view 35 through the center girder of the car showing the hopper-door controlling mechanism. Fig. 4 is a longitudinal vertical sectional view of the actuating pawl crank, and; Fig. 5 is a front elevation of the actuating pawl.

40 The car illustrated is composed of fabricated metal construction mounted upon two trucks of four wheels each as is customary and carries within the superstructure thereof the hopper shaped receptacle comprising 45 the side walls 1 and 2 and end walls 3 and 4, the truncated apex of which terminates intermediate the four innermost wheels of the two sets of trucks. My modification of such car hopper resides in the fact that the lower- 50 most approximately half of each side wall 1 and 2 is hinged to swing laterally and divided into three sections 5, 6 and 7 and the extreme lowermost portion of the end walls 3 and 4 are made somewhat wider than the 55 area necessary to make a tight receptacle

when the side walls or hinged doors are closed as indicated at 8 Fig. 2, this extra width being to prevent spewing of the discharging material when the side doors are open. The swinging doors 5, 6 and 7 at 60 each side of the car are pivotally hinged at their upper edges to the fixed portion of the side walls 1 and 2 by means of suitable butts 9, there being a pair of each such to each section of the door. The central section 6 of the swinging door is formed with the outwardly extending obtuse angle 10 therein about midway its height, this angle being for the purpose of providing greater carrying capacity for the hopper of the car 70 and also means whereby greater lateral relief is provided for the burden within the receptacle when the doors are opened, thus affording the greatest relief possible to the centermost portion of the load which invariably is the hardest compact portion. 75

A further object of the outwardly projecting angle of these doors is to provide means whereby they engage, when open, the side girders or angles 11 of the car and when 80 their lowermost free ends are still within the confines of the rails of the track upon which the car is mounted, that the load be discharged within such confines as is essential. Again this outward angle admits of 85 the doors being suddenly dropped against the side girders 11 to produce vibration throughout the car to assist in loosening any portion of the load which otherwise might tend to stick within the car, and for 90 which purpose I have designed the specially constructed door operating mechanism hereinafter more fully described and which differs materially from that illustrated in my former application upon a similar de- 95 vice.

The doors 6-6 are operated back and forth in unison by means of chains 12-12, one attached to each edge of the lowermost free end of each door and leading to suitable drums 13-13 mounted upon and actuated by the shaft 14 journaled within the longitudinal box-girder composed of the channel bars 15 and 16 and which girder comprises the principal strengthening mem- 100 ber of the car and preferably extends the entire length thereof.

A baffle plate 17 is fixed to the inner wall of each edge of the doors 6 forming an end wall thereto and the inner edge of which is 110

designed to impinge the outer edge surface of each of the doors 5 and 7 when the former is closed and thus hold the latter in place as shown upon the left side in Fig. 2, while 5 upon the right side of the same figure is illustrated the door 6 as being open in which case the side wings or doors 5 and 7 are free to rest upon the flanges of the innermost wheels of the car and while the door 6 10 swings entirely free of them.

It is evident that were the sections 5, 6 and 7 all combined integrally, the amplitude of the discharge opening of the hopper would be confined to the limits of the wheels, 15 while dividing them as illustrated admits of the center section swinging intermediate the wheels and free of the wing sections and thus materially increase the discharge opening and results in other essential benefits as are obvious.

Outside, and at one end of the burden hopper is a shaft 18 extending transverse the car and suitably revolvably mounted within the frame thereof and upon the center 25 girder, the ends of the shaft extending slightly beyond the limits of the sides of the car as to conveniently receive a suitable hand crank 19 by which the shaft 18 is manually actuated.

30 A bell-crank lever 20 is mounted upon the shaft 18 directly over the central box girder and carries within its free end the depending ratchet pawl 21, this latter being suspended within the bell-crank by means 35 of a ball and socket joint 22 to provide for universal movement of the pawl, the necessity of which is evident as the click 23 of the pawl 21 engages the ratchet wheel 24 and imparts revolving motion thereto when 40 the pawl is reciprocated.

Within the body portion of the pawl 21 is formed a rectangular elongated aperture 25 through which loosely protrudes the handle 26 of the stop pawl 27 which handle is 45 formed as an integral part of the pawl 27, the latter being pivotally supported upon a bracket 28 attached to the inner wall of the channel 15 and so arranged to freely engage the ratchet wheel 24 and when in such 50 engagement to effectually retard any backward or unwinding motion of the ratch 24 which similarly affects the shaft 14 and drum 13—13.

55 From the foregoing it is evident that when the pawl 21 is raised to the upward limit of its stroke by the revolving of the shaft 18, the lower end wall of the aperture 25 will engage and carry upward with it the handle 26 of the pawl 27 and thus raise 60 the latter from engagement with the ratch 24 which will admit of the shaft 14 being freely actuated by the action of the doors 6—6 through the medium of the chains 12 acting upon the drums 13—13, all of the 65 chains being wound about the drums from

the same side as clearly illustrated in Fig. 3. This free action of the doors 6—6 will permit them to drop open outwardly against the side girders 11 of the car and produce the before described vibration which will assist in discharging the contents of the car hopper and at the same time the wing doors 5—7 will fall open to the limits of the wheels of the car as above described and as illustrated upon the right side of Fig. 2. If it is found that the discharge does not freely take place, the doors may be drawn closed and again suddenly released to produce a further vibration of the car.

70 The closing of the doors by the winding up of the chains upon the drums 13—13 is accomplished in a similar manner as the opening thereof, respecting the shaft 18, except that the oscillatory motion of said shaft by the crank 19 is of much shorter stroke 75 and repeated until the shaft 14 is sufficiently revolved to bring the doors fully closed. In this latter case, it will be seen that as the pawl 21 engages the ratchet 24 and is forced downward, thereby revolving the ratch, the pawl 27 is free to engage the ratch also and will constantly hold all motion imparted to the ratchet, thus a continued short reciprocating motion of the pawl 21 will result in the winding up of the 80 chains 12 upon the drums 13—13 and closing of the doors, while as before stated, a more extreme upward motion of the pawl 21 will result in simultaneously releasing the pawl 27 which entirely frees the ratch to 85 90 95 100 be actuated by the weight of the doors.

I have illustrated in Fig. 2 of the drawings an impossible condition of the doors when my device is intact, that is of one door being closed and the other being open for 105 in operation they work simultaneously as is clearly evident, and the position in the illustration is simply for comparison.

Having thus fully described my invention what I claim and desire to secure by Letters Patent is:

1. The combination with a hopper car, of an opening upon either side of the hopper in the car, each opening having three swinging doors, the centermost door being directly 115 operated by means carried by the car and the side doors being indirectly operated thereby.

2. The combination with a hopper car, of openings within either side of the lowermost portion of the hopper of the car, a plurality of swinging doors covering each opening, means carried by the doors for engaging the car body, and means for releasing the said doors, whereby the car is vibrated to 120 assist in discharging the contents of the hopper.

3. The combination with a hopper car, of doors controlling the opening within the hopper, a shaft carried by the car outside 125 130

of the hopper and means whereby a maximum oscillatory motion of the shaft will open the doors of the hopper and a lesser oscillatory motion of the shaft will close 5 the doors of the hopper.

4. The combination with a hopper car, of an opening upon either side of the hopper each opening having three swinging doors, the center door being directly operated and 10 the side doors being indirectly operated.

5. The combination with a hopper car of openings within either side of the lower-most portion of the hopper, a plurality of swinging doors covering each opening, and 15 means carried by the car for operating one of the doors independently of the other doors, all of the said doors adapted to engage the car body for the purpose described.

6. The combination with a hopper car, of 20 doors controlling the opening within the hopper, a shaft carried by the car, and means operated by the said shaft for both supporting and releasing the said doors all in one continuous operation.

25 7. The combination with a hopper, of doors, said doors controlling the opening within the hopper, an oscillating shaft for closing the doors, and means whereby a maximum rotation of the shaft releases the 30 doors.

35 8. The combination with a hopper car, of openings within either side of the lower-most portion of the car, a plurality of swinging doors covering each opening, cables 40 connected to the doors, combined means for swinging the said cables for closing the doors, and also for releasing the doors.

45 9. The combination with a hopper car, of openings within either side of the lower 40 end of the car, a plurality of swinging doors covering said openings, a shaft and a winding drum carried by the shaft chains connected to the door and passing around said drum, a wheel carried by said shaft and having ratchet teeth thereon, a pawl engaging 50 said ratchet and adapted to rotate the drum shaft a second pawl normally engaging the ratchet and means operated by the first-mentioned pawl for releasing the last-mentioned pawl substantially as shown and described.

55 10. The combination with a hopper car of openings within the lower end of the car, a plurality of swinging doors covering each opening, a shaft, a drum mounted on the shaft chains connected to the swinging doors and passing around the said drum, a ratchet carried by the shaft, an oscillating shaft

above the drum, a pawl connected to the oscillating shaft and engaging the ratchet, 60 a second pawl engaging the ratchet and having an outwardly extending handle passing through the first-mentioned pawl whereby an abnormal upward movement of the first-mentioned pawl releases the second-men- 65 tioned pawl for releasing the door-holding chains.

11. The combination with a hopper of openings within either side of the lower end of the car, a plurality of swinging doors 70 covering each opening, a shaft a drum carried by the shaft, chains connected to the swinging doors and passing around the drum from the same side, a ratchet carried by the shaft, a secured shaft carried by the 75 car above the drum, a pawl having a ball and socket connection with the said secured shaft and engaging the ratchet, an arm carried by said ratchet and passing through the first-mentioned ratchet whereby an abnor- 80 mal upward movement of the first-mentioned ratchet releases the second-mentioned ratchet.

12. The combination with a hopper car, of 85 openings within either side of the lower-most portion of the car, a plurality of swinging doors covering each opening, several of the said doors having an outwardly bulged portion, means for closing the said doors, and for releasing said doors, where- 90 by the said bulged portion of the doors may strike the car body.

13. The combination with a hopper car, of 95 openings within either side of the lower-most portion of the car, a plurality of swinging doors covering each opening, means connected to several of the said doors for closing and opening them, the rest of the doors operated by the aforementioned doors, the parts arranged as and for the 100 purpose described.

14. The combination with a hopper car, of doors controlled within the hopper, means for operating several of the said doors, baffles mounted on the said operated doors for 105 closing the other doors, the said operating doors having outwardly bulged portions, the parts arranged as and for the purpose described.

In testimony whereof I hereunto affix my 110 signature in the presence of two witnesses.

HJALMAR ZAHL.
